Primary Examiner — Michelle E. Wilson*Assistant Examiner* — Clese Moore, Jr.*(74) Attorney, Agent, or Firm* — Cantor Colburn LLP(57) **CLAIM**

The ornamental design for the racks for cycles or motorcycles, as shown and described.

DESCRIPTION

FIG. 1 is a perspective view of the racks for cycles or motorcycles showing my new design;

FIG. 2 is a front elevational view thereof;

FIG. 3 is a rear elevational view thereof, opposite that of FIG. 2;

FIG. 4 is a side elevational view thereof;

FIG. 5 is a side elevational view thereof, from a side opposite that of FIG. 4;

FIG. 6 is a top view thereof; and,

FIG. 7 is a bottom view thereof.

The broken lines shown in the drawings illustrate portions of the racks for cycles or motorcycles that form no part of the claimed design.
